[57] CLAIM

The ornamental design for a combination table and carrier or the like, as shown and described.

DESCRIPTION

FIG. 1 is a perspective view of the combination table and carrier or the like showing our new design.

FIG. 2 is a side elevational view thereof, the opposite side being substantially a mirror image.

FIG. 3 is a top plan view thereof.

FIG. 4 is a bottom plan view thereof.

FIG. 5 is a end elevational view thereof.

FIG. 6 is a opposite end elevational view thereof.

FIG. 7 is perspective view of a modification thereof.

FIG. 8 is a side elevational view thereof, the opposite side being substantially a mirror image.

FIG. 9 is a top plan view thereof.

FIG. 10 is a bottom plan view thereof.

FIG. 11 is a end elevational view thereof;

FIG. 12 is an opposite end elevational view thereof.
